UNITED STATES PATENT OFFICE.

ALBERT B. RYPINSKI, OF LAURELTON, NEW YORK, ASSIGNOR TO THOMAS E. MURRAY,
OF BROOKLYN, NEW YORK.

FUSE AND CUT-OUT MECHANISM.

Application filed May 16, 1924. Serial No. 713,663.

To all whom it may concern:

Be it known that I, ALBERT B. RYPINSKI, a citizen of the United States, and resident of Laurelton, Long Island, New York, have 5 invented certain new and useful Improvements in Fuse and Cut-Out Mechanism, of which the following is a specification.

My invention aims to provide certain improvements in fuse and cut-out mechanisms 10 such as are generally used in entrance boxes for electric circuits.

The accompanying drawings illustrate an embodiment of the invention.

Fig. 1 is a plan partly broken away;

15 Figs. 2 and 3 are vertical sections approximately on the correspondingly numbered lines in Fig. 1.

Referring to the embodiment of the invention illustrated, the various parts are 20 mounted on a block of porcelain or similar non-conducting material which is adapted to be fastened on the bottom 1 of a box or other support. The block 2 of porcelain is of approximately rectangular shape in plan 25 and is formed with certain grooves and barriers for mounting the terminals and preventing short circuits between them. In Fig. 1 there are indicated screws 3 for attaching the block to bosses 4 on the support 1.

A shallow groove or recess 5 is formed at one side of the block surrounded by a raised barrier 6. In this groove is located a terminal plate 7 riveted or otherwise fastened on the porcelain block and having threaded through it a binding screw 8 for the end of a wire. The terminal 7 is bent upward at one edge and carries a pair of spring contacts 9.

At the other side of the same end of the block there is a groove or recess 10 at a lower level and in which is mounted a terminal 11 carrying a binding screw 12, this terminal being projected upward at one side and carrying a pair of spring contacts 12 at a lower level than the contacts 9. The two pairs of contacts 9 and 12 are intended to be bridged by a fuse as hereinafter described.

At the other side of the center of the block from the two fuse contacts, there are grooves 13 and 14 separated from each other by a barrier 15. At each end of the groove 13 there is a deeper recess, these recesses carrying terminal plates 16 and 17 fastened in place and provided with binding screws for the ends of wires. The two plates

16 and 17 are bridged at their inner ends by a strip 18 fastened to the porcelain block by means of screws shown. These terminals 16 and 17 with their detachable connecting strip 18 may provide a means of 60 opening the circuit in meter testing. The barrier 15 is formed at an intermediate point in its length with an elevated portion 19 serving as a stop and referred to hereinafter.

The ends of the groove 14 are also depressed and carry terminal plates 20 and 21 for the neutral of a two-wire circuit, one plate serving ahead of the meter and one after the meter, each of these plates being provided with a pair of binding screws for 70 the incoming and outgoing wires respectively. The equipment of terminals and bridges or cut-outs above described is a common one. There are various others in use, some simpler and some involving a more 75 complicated arrangement. Generally speaking, the invention is applicable to various arrangements of the usual or suitable types.

An important feature of the present invention is the mounting of the fuse and connections. On a central boss of the base or block 2, there is mounted a rocking arm of porcelain carrying the fuse and fuse terminals. The fuse-carrying arm has a hub 22 through which passes a hollow shaft 23 80 flanged over the top of the hub 22, with a reduced lower end entering the base block 2. A nut 24 located in a socket on the underside of the base block is threaded on to the lower end of the hollow shaft 23. The rocking 85 arm is preferably of porcelain, and a metal plate 25 is interposed between it and the base block 2 to reduce friction. The end of the porcelain arm is formed as a socket 26 for the fuse. The fuse may be of various types. 90

An ordinary fuse 27 is shown of porcelain with a threaded metal ring 28 around it and with a metal button 29 at the end, these two parts being connected by a fuse inside the block. In the socket 26 is carried a threaded shell 30 which makes contact at its lower end with a blade 31 which is bent and directed in such a position as to enter the spring contacts 9. In the bottom of the socket is a screw 32 the head of which is engaged by the button 29; this screw being insulated from the surrounding parts and threaded into a terminal 33 which is bent around in position to enter between the spring contacts 12.

In the position of the parts shown, the 110

fuse is connected between the terminals 7 and 11. When it is to be disconnected, the porcelain arm is swung about the pivotal shaft 23 (upward in Fig. 1), until blade 33 or other part strikes the stop 19. In this position the terminals 31 and 33 are widely removed from the switch plates 9 and 12, the blade 31 swinging clear above the contacts 12 as will be clear from Fig. 3. The 10 arm is pivoted on the elevated central portion of the block 2 so as to swing clear above all the contacts at the side opposite the fuse terminals.

In the position of use the permanent connections are entirely unobstructed by the swinging arm, so that access can be easily had thereto with a screw driver. And for manipulating the terminals 7 and 11 or the binding screws thereof access is also easier 20 because the end of the arm is only big enough to enclose the fuse and because the terminals 7 and 11 are located outside of the periphery of the end of the arm. Or the arm may be swung to the opposite position 25 to give easier access to these parts.

The rocking arm may be operated by various devices such, for example, as the operating lever pivoted to the cover of the casing illustrated in an application of Emil T. 30 Hagist, No. 718,326, filed June 6, 1924, or by devices similar to those described in an application of Thomas E. Murray No. 556,818, filed April 25, 1922, and an application of Murray and Blackwood, No. 587,189 filed 35 September 9, 1922. The invention may be applied in whole or in part to mechanisms employing two or more fuse sockets and sets of switch contacts. The provision of the fuse socket and hub of the arm in an integral structure of insulating material 40 simplifies the construction greatly. The extending of the rocking arm to one side only of its axis facilitates easy access to the terminals arranged on one side of the block and, 45 when the arm is shifted to the open position, to the switch contacts located on the opposite side of the block. And such access is further facilitated by the mounting of the arm at a point between the switch contacts 50 9 and 12 at one side and the terminals with binding posts at the other side and by the capacity of the arm to rock to a range greater than 90 degrees.

Though I have described with great particularity of detail a certain embodiment of

my invention, yet it is not to be understood therefrom that the invention is restricted to the particular embodiment disclosed. Various modifications thereof in detail and in the arrangement of the parts may be made by those skilled in the art without departure from the invention as defined in the following claims.

What I claim is:

1. A cut-out mechanism including in combination a base block and a rocking arm mounted on said block and comprising in an integral structure of insulating material a pivoted hub and a fuse socket, said hub being pivoted about an axis transverse to the face 70 of the base block.

2. A cut-out mechanism including in combination a base block and a rocking arm mounted on said block carrying a fuse socket and switch contacts for co-operation 75 with contacts mounted directly on the base block, said arm moving in a path substantially parallel with the face of the base block and having a range of movement greater than ninety degrees.

3. A cut-out mechanism including in combination a base block and a rocking arm mounted on said block comprising an integral structure of insulating material carrying a pair of fuse terminals and carrying 85 switch contacts for co-operation with contacts mounted directly on the base block, said arm extending to one side only of its axis.

4. A cut-out mechanism including in combination a base block and a rocking arm mounted on said block carrying a fuse socket and switch contacts for co-operation 90 with contacts mounted directly on the base block, said arm moving in a path substantially parallel with the face of the base block 95 and extending to one side only of its axis and having a range of movement greater than ninety degrees.

5. A cut-out mechanism including in combination a base block carrying switch contacts at one side and terminals at the opposite side, a rocking arm mounted on said block at a point between said switch contacts and said terminals carrying a fuse 105 socket and contacts for co-operation with the switch contacts on the base block.

In witness whereof, I have hereunto signed my name.

ALBERT B. RYPINSKI.
